UNITED STATES PATENT OFFICE.

SAMUEL WALCOTT BROWN, OF COLORADO SPRINGS, COLORADO.

CHUTE.

No. 888,386.

Specification of Letters Patent.

Patented May 19, 1908.

Application filed August 17, 1907. Serial No. 389,034.

To all whom it may concern:

Be it known that I, SAMUEL W. BROWN, a citizen of the United States, and a resident of Colorado Springs, in the county of El Paso and State of Colorado, have invented a new and Improved Chute, of which the following is a full, clear, and exact description.

This invention relates to chutes, and more particularly to chutes for coal or other broken or granular material.

An object of the invention is to provide a simple, strong and light chute adapted to be arranged at an opening in a wall and having a tilting hopper for directing the material 15 through the opening and serving as a closure for the opening when the hopper is in an inoperative position.

A further object of the invention is to provide a chute for directing broken and granular material such as coal through an opening in a wall, and having a guard for preventing the marring of the wall by the passing material when the chute is in use.

The invention consists in the construction 25 and combination of parts to be more fully described hereinafter and particularly set forth in the claims.

Reference is to be had to the accompanying drawings forming a part of this specification, in which similar characters of reference indicate corresponding parts in all the views and in which

Figure 1 shows a part of a wall with my chute applied thereto and arranged in a closed position; Fig. 2 is a section on the line 2—2 of Fig. 1; Fig. 3 is a section on the line 3—3 of Fig. 1, showing parts broken away; Fig. 4 is a section on the line 4—4 of Fig. 2; Fig. 5 is a section on the line 5—5 of Fig. 2; Fig. 6 is a section on the line 6—6 of Fig. 1; and Fig. 7 is a section on the line 7—7 of Fig. 1.

Referring more particularly to the parts, 1 represents a part of a wall of a house or 45 other building having an opening for the introduction therethrough into the building, of broken or granular material such as coal, crushed stone and the like.

I provide a casing preferably of sheet metal 50 or similar material adapted to be arranged in the opening in the wall and comprising sides 2, a top 3 and a bottom 4. The bottom 4 is arranged at an angle with the horizontal and constitutes an apron for directing the material 55 from the opening into the interior of the building. A frame 5 of suitable form is ar-

ranged at the edge of the opening and is secured to the casing at laterally disposed edges thereof by means of rivets 6. At the inner edges, the casing is strengthened by having the material folded back upon itself to form flanges 7 and 8. The casing is secured in position at the opening by means of side bolts 21 having threaded extremities 22 arranged in openings of the sides and held in position by means of washers 23 and nuts 24. The side bolts extend laterally to adjacent supports such as the walls of the building and are rigidly fastened thereto in any suitable manner.

The tilting hopper is mounted to swing upon the lower side of the frame 5 and comprises side walls 9 and a bottom 10 formed from a single piece of sheet metal or other similar material. The bottom 10 of the tilting hopper forms a closure for the opening in the wall 1 and is strengthened by means of end and side reinforcing strips 11 and 12 respectively, secured in position by means of rivets 13. The bottom or closure 10 is further reinforced by means of transverse strips 14 connecting the side strips 12 and secured in place by means of rivets 15. Between the strips 11 and 14 and the bottom 10 of the tilting hopper are spacing strips 11^a and 14^a respectively. At the upper, inner edge the bottom 10 has a further reinforcing strip 16 secured in position by the rivets 13 and provided with laterally disposed ends 17 disposed against the side walls 9. At the inner edges the latter have reinforcing strips 18 held in position by means of rivets 19 and connected by an integral transverse member 20 extending from side wall to side wall. The end strips 11 and the side strips 12 extend laterally beyond the edges of the bottom 10 and engage the frame 5 to limit the inward movement of the hopper. The transverse member 20 engages the inner side of the frame to limit the outward movement of the 100 tilting hopper.

The end strips 11 and the transverse strips 14 of the tilting hopper bottom have the ends adjacent to the lower edge of the frame 5 folded back and formed into bearing sleeves 105 25. Similar bearing sleeves 26 are mounted at the lower side of the casing 1 by means of rivets 27. When the hopper is properly located in the opening the sleeves 25 and 26 are in alinement and are joined by a pivot or hinge rod 28 passing therethrough and serving to hinge the hopper to the casing. The

side walls 9 have a plurality of openings 29. Each of the side walls has a pivot bolt 30 arranged in one of the openings 29, adjacent to which are located washers 31 having openings 5 to receive the pivot bolt. A guard 32 consisting preferably of a sheet metal plate is mounted upon the pivot bolts 30 by means of brackets 33. Nuts 34 are arranged upon the threaded bolts 30 to hold the brackets in 10 position. A helical spring 35, is carried by each of the bolts 30 between the adjacent brackets 33 and the adjacent side wall 9. The brackets are secured to the guard by means of rivets 36. The brackets are extended across the apron and reinforce the 15 same. When the hopper is in the inoperative position, closing the opening in the wall, the guard is arranged between the side walls with the edge adjacent to the bottom 10 of 20 the hopper. When the hopper is swung or tilted outward into the operative position, the guard is swung upward against the wall and protects the wall from marring or injury due to the material passing rapidly through 25 the chute. The guard can be swung upward against the wall of the building by hand without difficulty, a recess 37 at the edge permitting the hand of the operator to be inserted under the edge.

30 The top of the casing at the under side carries a spring latch 38, mounted upon the casing by means of rivets 39, and projecting outwardly through an opening 40 in the frame 5. The latch at the projecting end has 35 a shoulder 41 and an opening 42.

A catch socket 43, is mounted upon the upper side strip 12 of the bottom 10 by means of rivets 44, and projects laterally beyond the edge, presenting an opening 45 at the 40 projecting extremity. The opening 45 is arranged to receive the end of the spring latch when the hopper is in the closed position, the extremity of the latch being curved to permit the socket to displace the latch in 45 passing over the same and to engage at the shoulder 41 to be held firmly in position thereby. A pad-lock 46 can be arranged in the opening 42 of the latch when the hopper is in the inoperative position, to lock the 50 closure in position at the opening, and thereby to prevent unauthorized entrance to the building through the opening in the wall. The end of the socket 43 opposite the opening 45 terminates in a handle 47, by means 55 of which the hopper can be easily manipulated.

The lower edge of the bottom 10 of the hopper extends inwardly beyond the lower side of the frame, thereby turning the material 60 from the edge and preventing the gathering of a quantity of the material which would hinder the operation of the hopper. Furthermore, the arrangement of the apron 4 and the bottom 10 is such, that the angular- 65 ity thereof when the chute is in operation

prevents any of the material from collecting in and choking the chute when the latter is in use. When the hopper is swung into the closed position, the guard will be forced into engagement with the catch or adjacent portions of the frame, and will thereby be automatically swung into position between the sides of the hopper as the latter is closed. The springs between the brackets 33 and the side walls of the hopper permit certain 70 resilient play of the apron when it is operated, whereby is avoided any possibility of the jamming or binding of the latter.

As I provide a plurality of openings 29 in the side walls 9 of the hopper, it is possible 75 to mount the guard 32 adjustably to make allowance for the form and construction of the wall against which the guard rests when in an operative position.

It will be understood that the wall adjacent 80 to the coal chute may be provided with a projecting flange or cornice or other projection, which would interfere with the guard if the latter were hinged to the side walls at points close to the wall. By means 85 of the openings 29 however, and the pivot bolt 30, it is possible to arrange the guard in position so that it will clear the projection of the wall when swung into the upward position against the same when the hopper is 95 tilted outward.

Having thus described my invention, I claim as new and desire to secure by Letters Patent:—

1. In a chute, a casing adapted to be 100 mounted at an opening in a wall, a tilting hopper hinged to said casing and constituting a closure for the opening, and a guard carried by said hopper and mounted to be swung into position to protect the wall when the hopper is open, said guard automatically swinging into an inoperative position within 105 said hopper when the latter is closed.

2. In a chute, a casing adapted to be mounted at an opening in a wall, a tilting 110 hopper hinged to said casing and constituting a closure for the opening when said hopper is closed, and an adjustable guard carried by said hopper and mounted to be swung into position to protect the wall when 115 the hopper is open.

3. In a chute, a casing adapted to be mounted at an opening in a wall, a tilting hopper hinged to said casing and constituting a closure for the opening, a guard 120 pivotally mounted upon said hopper and arranged to be swung into position to protect a wall when the hopper is open, and means for locking the said hopper in a closed position, said guard automatically swinging 125 into an inoperative position within said hopper when the latter is closed.

4. In a chute, a casing adapted to be mounted at an opening in a wall, a tilting 130 hopper comprising a bottom and sides in-

tegral therewith, said hopper being hinged to said casing, the bottom of said hopper constituting a closure for the opening and having lateral extensions engaging at the 5 edges of the opening, and an adjustable guard pivotally mounted upon said hopper and arranged to be swung into position to protect the wall when the hopper is open.

5. In a chute, a casing adapted to be mounted at an opening in a wall and having a frame arranged at the edges of the opening, a tilting hopper hinged to said frame and comprising a bottom and sides integral therewith, said hopper having means for limiting 10 the movement thereof, and a guard pivotally mounted upon said hopper and arranged to be swung into position to protect the wall when the hopper is open, said guard automatically swinging into an inoperative position 15 within said hopper when the latter is closed.

6. In a chute, a casing adapted to be mounted at an opening in a wall and having an inclined apron, a frame rigidly carried by said casing and arranged at the edges of the 20 opening, a tilting hopper hinged to said frame and comprising a bottom and sides integral therewith, said bottom of said hopper constituting a closure for the opening and having 25 strips extending laterally therefrom to engage said frame to limit the movement of the hopper in one direction, a stop carried by said hopper and adapted to limit the movement thereof in the opposite direction, and a guard adjustably mounted between the sides 30 of said hopper and arranged to be swung into position to protect the wall when the hopper is open.

7. In a chute, a casing adapted to be mounted at an opening in a wall and having 35 an inclined apron, a frame rigidly mounted upon said casing and arranged at the edges of the opening, said frame having a hinge sleeve, a tilting hopper comprising a bottom and sides integral therewith, said bottom of said 40 hopper having reinforcing strips and edge strips extending laterally beyond the bottom, said edge strips being adapted to engage said frame to limit the movement of the hopper in one direction, one of said strips of said bottom having formed thereon a hinge sleeve, a 45 hinge pin mounted in said sleeves and pivotally connecting said frame and said bottom, and a guard pivotally mounted at the sides of said hopper and arranged to be swung into 50 position to protect the wall when the hopper is open.

8. In a chute, a casing adapted to be mounted at an opening in a wall and having 55 an apron, a frame rigidly mounted upon said casing and arranged at the edges of the open-

ing, a tilting hopper comprising a bottom and sides integral therewith, a hinge connecting said frame and said bottom, said bottom being adapted to engage said frame to limit the movement of said hopper in one direction 65 and constituting a closure for the opening, a transverse member connecting said sides and serving as a stop to limit the movement of said hopper in the opposite direction, and means for holding said member in a closed 70 position, and a guard pivotally mounted between said sides and arranged to be swung into position to protect the same when said hopper is open, said guard automatically swinging into an inoperative position within said hopper when 75 the latter is closed.

9. In a chute, a casing adapted to be mounted at an opening in a wall, a tilting hopper pivotally mounted at said casing and having a bottom and sides integral therewith, 80 brackets adjustably carried by said sides, and a guard pivotally mounted upon said brackets and arranged to be swung into position to protect the wall when the hopper is open.

10. In a chute, a casing adapted to be 85 mounted at an opening in a wall, a tilting hopper pivotally mounted at said casing and comprising bottom and sides integral therewith, said sides having a plurality of openings, pivot bolts adapted to be removably 90 arranged in openings in said sides, brackets mounted upon said bolts, resilient means for spacing said brackets from said sides, and a guard rigid with said brackets and arranged to be swung into position to protect the wall 95 when said hopper is open.

11. In a chute, a casing adapted to be mounted at an opening in a wall and having a frame arranged at the edges of the opening, a tilting hopper mounted to swing upon said 100 frame and comprising a bottom and sides integral therewith, a transverse member carried by said sides and serving as a stop to limit the outward movement of said hopper, said sides having a plurality of openings, 105 bolts adapted to be removably mounted in said openings of said sides, brackets mounted upon said bolts, springs upon said bolts between said sides and said brackets, and a guard carried rigidly by said brackets and arranged to be swung into position to protect the wall when the hopper is open, said brackets being extended to reinforce said guard. 110

In testimony whereof I have signed my name to this specification in the presence of 115 two subscribing witnesses.
